THERMALLY ACTUATED APPARATUS

Arthur George Bullen, Sefton Park, Liverpool,
EnglandApplication August 12, 1933, Serial No. 634,883
In Great Britain August 19, 1932

9 Claims. (Cl. 200—142)

This invention relates to thermally operated apparatus employing substances, such as wax and the like, which upon the application or extraction of heat undergo physical changes which are applied to offer variable resistance to the movement of metal, glass, porcelain or other substances associated with the thermally effected substance, hereinafter referred to as "wax", which term is intended to include all fusible substances having the following characteristic properties dependent upon the quantity of contained heat, viz: hardening or softening as the quantity of heat applied or extracted varies, whether accompanied by changes in temperature of the substance or otherwise, fluidity, tenacity, adhesion, viscosity, volumetric variation including gas emissions or condensation, surface tension and like physical characteristics influenced by heat. For the purpose of convenience, the term "wax" will be considered as having heat applied in describing the invention, when heat is extracted the operations will be reversed as is understood.

In particular this invention is intended to carry into practical effect some of the apparatus described in my specification No. 378,586, to permit some of the wax cartridges to be adapted for use with the present invention, to interchange these cartridges and permit adjustments of calibration, to enable the associated wax cartridges to be reset after each actuation, and some further methods of actuation not restricted to the heating effect of an electric current nor the wax cartridge included in the previous specification. For example, while the present invention is intended as a protective device for electrical apparatus primarily, and as such will mainly take the form of a switch to actuate an alarm or conductor circuit, it is not intended to restrict its application to switchgear or means to interrupt circuits, its use may be applied to other purposes where thermal control or actuation is required.

As a thermally operated apparatus for the protection of electrical plant, my invention is intended to be actuated by excessive rise in the temperature of the electrical plant and in turn, my invention is intended to actuate apparatus intended to deal with such excessive rise of temperature which may result in a breakdown of the said plant, in addition to giving warning that the said plant requires attention.

For example, my invention may be actuated by the heating effect of an excess current carried by its associated wax cartridge, but in cases where heavy loads are carried for short periods, it may

be preferable to actuate my invention only in the event of the short period loads being exceeded, the duration causing a temperature rise in the plant concerned. Again, rise of temperature may be due to failure of the means employed to dissipate the heat set up in the electrical plant, such as failure of air, oil or water, however circulated, for cooling purposes, or due to the cooling air, oil or water being in turn insufficiently cooled before re-circulation due to atmospheric temperature conditions. Further the bearing of running the plant may overheat due to mechanical defect or defect in the oil circulation. If due to the lubricating system it may not be desirable to stop the running plant, but to give warning and at the same time actuate a supplementary oil supply to prevent seizing of the bearings. Bearing troubles apply equally to other than electrical machinery, and my said invention is intended for application to such.

According to this invention a container is provided with a wax substance and a mechanical member is secured in a fixed relationship to the container by means of the wax substance when hard, but when the latter is softened by heat applied, the relative position of the container and mechanical member may be altered, and such movement or alteration is utilized for actuating other mechanism.

The accompanying drawings show diagrammatically some embodiments of this invention in which:

Fig. 1 shows the invention applied to a three phase circuit for tripping a main switch.

Fig. 1^a is a front elevation of a switch with cover removed applied to the circuit shown in Fig. 1.

Fig. 2 is a sectional elevation of a compression type of switch.

Fig. 3 is a sectional elevation of another form of switch.

Fig. 4 is a sectional elevation of a fixed heating coil type of switch.

Fig. 5 is a sectional elevation of a further modification.

Fig. 6 is an elevation at right angles to Fig. 5.

Fig. 7 shows a still further modification of switch and,

Fig. 8 is a plan view of Fig. 7.

According to some embodiments of this invention which are in the form of a switch in which the cartridge described in my British Patent specification No. 378,586 will be adapted as follows:—The switch contacts will be placed in their "on" or "off" position as desired hereinafter re-

ferred to as "normal position", against the opposition of a force intended to actuate them, hereinafter referred to as "actuating force" or "actuated position". The actuating force is opposed, 5 for example by a wax cartridge comprising a helical spring encased in wax, said spring designed in its mechanical arrangement, to be weaker in its resistance to the actuating force unless reinforced by the wax substance associated 10 with it, in the present instance, the wax contained in the cartridge when the latter has not reached the operating temperature. When the operating temperature is reached, the supplementing resistance of the wax to the movement 15 of its associated helical spring becomes insufficient to resist the force tending to actuate the switch, this actuating force then predominates and the switch is actuated.

As an example:—A contact is supported on a 20 moving arm and against the action of a retractive spring, said arm is moved forward until its contact meets a fixed contact. The arm is retained in position by means of a trigger or catch mechanism which may take the form of a lever 25 upon which is mounted a contact arranged as a catch or locking device. If the retaining means is of a lever type, one end is secured to a locating terminal block so arranged that the moving arm when moved to the normal position, raises the 30 lever from the locating terminal block until the catch mechanism is engaged. The opposite end of the lever is secured to a wax cartridge terminal cap, hereinafter described which may be raised or depressed, when the wax within the 35 cartridge softens due to the circuit current passing from the spring within the cartridge, its terminal cap and lever to the moving arm. The retractive force tending to actuate the moving arm and thereby the circuit controlled, tends to raise 40 or lower the cap fitted to the cartridge, due to the arrangement of the lever. When the wax softens in the cartridge sufficiently to permit the lever to move the cap, the catch mechanism is released, the moving arm actuates the circuit, 45 and the force exerted previously on the cartridge cap being released, the latter returns to its normal position because of its inherent tension unrestrained by the softened wax, in this position the wax cools and hardens when the switch operation 50 may be repeated indefinitely.

The cartridge may be carried by a moving arm or occupy a fixed position according to the type of switch required, or itself may constitute the moving switch contact or contact support in 55 which case the cartridge cap would constitute one contact and the lower end of the cartridge would be hinged to permit the circuit opening contacts to move apart due to the pressure of springs, gravity or the like.

60 The lever action will not be required in all types of switches, but has an important application in cases where contact pressure is important and the mechanical strength of the spring within the cartridge is insufficient to directly enable this 65 pressure to be effected. Further, since the adjustment of pressure or lift, at the cartridge cap due to the retractive force on the switch moving parts being applied through a lever arrangement, it is possible to further calibrate the apparatus 70 employing the cartridge, since the degree of softness of the wax associated with the spring will influence the point at which the retractive force can operate the switch mechanism, adjustment of leverage proportions enables individual cartridges 75 to be further calibrated.

This invention may be used in combination with apparatus of a known kind, for example, with coil operated overload switches to which it may provide the time lag features. The mechanical arrangements described are principally 5 intended for application with wax and the like substances which are insulators of electricity, but the invention is not restricted to such, should it be desired to actuate the apparatus described by other types of thermal elements, metal alloys, 10 bimetal strips and the like.

Referring to Fig. 1 two switches 1 and 2 are provided for controlling a main switch 3 in a three phase circuit A, B, C, connected to an electric motor 4. The thermal elements of the 15 switches 1 and 2 are in series with the main current circuit of phases A and C between the main switch 3 and motor 4, the middle phase wire B passes direct to the electric motor 4.

A trip or shunt coil 5 is connected across the 20 two phases A and C in such a manner that if either of the switches 1 or 2 is operated the trip coil circuit is interrupted and then the main switch as herein set forth.

The switches 1 and 2 each consist of a metallic 25 container 6 which are connected in series with the respective phases A and C as shown in Fig. 1, being supported in an insulated mounting 6a (only one shown). A helical spring 1 having the upper coils of a smaller diameter than the lower ones 30 has the lower end 8 fixed to the base of the container 6. The containers 6 are partly filled with a wax substance, so that when the wax substance is solid the larger coils are embedded therein. The advantages of providing a spring with the 35 upper coils of smaller diameter than the lower coils, is that, the mechanical strength of the smaller coils are greater than the larger coils, further the smaller convolutions will cut their way through any wax that has risen in the container. The upper end of the spring is fixed to a 40 rocking lever 9 with contact 9a, which in turn, is loosely supported upon a rod 10 fixed in the insulated mounting 6a. The movement of said rocking lever 9 upon the rod 10 is limited in one 45 direction, by means of a collar 11 fixed to the rod 10, and in the opposite direction by a helical spring 12 arranged on the rod 10 in a recess in the mounting 6a and a stop 9c as shown in Fig. 1, whereby the rocking lever 9 is free to move when 50 the wax is solid in order to close the circuit.

A pivoted switch arm 13 is adapted to engage with the rocking lever 9 against tension of a helical spring 14 when the circuit is closed, and a spring controlled plunger 9c is adapted to open 55 the circuit when the wax is solid.

The operation of the switch is as follows:—

The switch arms 13 are first closed and the motor is then started up in the usual manner. Assuming the main circuit requires fifty amperes 60 per phase the trip coil may only require one ampere, should there be an excess of over fifty amperes in any one phase, one of the metal containers are heated causing the wax to soften or melt and release the trip coil switch, if there 65 is more than one ampere in the trip coil circuit, then the helical spring is heated, causing the wax to soften or melt, thereby releasing the trip coil and the main switch.

The content 9a can either be depressed automatically through the softening or melting of the wax or by hand. In the automatic operation, the pressure of the contact 13 acting upon the contact 9a through the tension of the spring 14 is unable to compress the spring 12 which 75

latter, is purposely made stronger. The pressure of contact 13 on contact 9^a also tends to raise the end of the rocking lever 9 at the opposite end to the contact 9^a by stretching the spring 7, which is prevented when the wax is solid. When the wax softens the spring 7 lifts, the smaller diameter of the coils cutting their way through any wax that has risen in the container 5, the rocking lever 9 is tilted when the contact 9^a is lowered and contact 13 rides over and away from contact 9^a through the tension of the spring 14 acting upon the contact 13. As soon as the contacts are broken the natural tension of the spring 7 tilts the rocking lever 9 in a reverse direction, the movement being limited by a stop 9^b, and in addition the spring 12 also tends to force the rocking lever 9 into a horizontal position. As soon as the wax becomes solid the switch can be closed again. To open the switch by hand it is only necessary to apply a momentary pressure upon the end of the plunger 9^c in order to depress the contact 9^a when the circuit is broken as herein set forth.

The switch is again closed before the wax becomes solid.

Fig. 1^a shows a complete operative embodiment of the switch 1 of Fig. 1, with the addition of a plunger 9^d for closing the contact 13.

Referring to Fig. 2 a container 15 is provided with a helical spring 16 partly embedded in wax. The upper coils are of a smaller diameter than the lower coils as herein set forth. The lower end of the spring 16 is connected to a terminal 17 and the upper end is fixed to a ball or roller contact member 18, whose upward movement is limited by a flange 19 integral with the ball contact member 18.

A contact arm 20 rotatably mounted in the upper part of the container 15^a is retained in position by means of a spring controlled plunger 21, which may serve as a terminal and said contact arm 20 is moved by means of a switch arm 22 against the tension of a helical spring 23.

The switch is closed by hand when the wax is solid, by pulling the switch arm 22, when the lower end of the contact arm 20 will slide over the ball or roller member 18 and the spring controlled plunger 21 allows for the upward movement of said contact arm 20.

When the wax softens through an overload passing through and heating the helical spring 16, this said spring is compressed due to the tension of the spring 23 which moves the contact arm to the off position, and during this said movement, the ball or roller contact 18 moves downward and the spring controlled plunger 21 will remain stationary by reason of the tension of the spring 16 being less than that of the spring controlled plunger 21. As soon as the contact arm 20 has moved over the ball member 18 to the off position, this ball will again rise into its normal position by the tension of the spring 16, and when the wax is solid, the switch can be closed again.

Referring to Fig. 3 a porcelain insulator 24 has a helical spring 25 with coils of two different diameters inserted in a central aperture 26, said spring 25, serving as a conductor is connected at the base of the insulator to a terminal through a plug 27. The upper end of the spring 25 is connected to a lever 28 pivotally supported in a bracket 29 which in turn is fixed to the insulator 24. The upward movement of said lever 28 is limited by a stop 29^a.

A contact arm 30 pivotally connected to the lever 28, the lower end of said arm descending a short distance beneath the lever 28, is provided with extensions 31 adapted to move along a slotted ramp 32, the lower end of the arm 30 is 5 connected to the bracket 29 by means of a helical spring 33, at angle to the lever 28 in order to counteract against the weight and leverage of arm 30 and weight and leverage of lever 28. The upper end of the arm 30 is formed with 10 a contact preferably consisting of a grooved wheel 34 which engages with a roller 35 fixed to a bracket 36 suspended by relief springs 37, from an overhead line 38, or another insulator. The electrical circuit is from, the overhead line 15 38 relief springs 37, bracket 36, roller 35, grooved wheel 34, arm 30, lever 28, and spring 25.

The provision of the relief springs 37 is to allow for the vertical movement of the bracket 36 so that the contact 34 on the end of the arm 30 can 20 slide under the roller 35 when the wax is solid, in order to close the switch. Any suitable means may be provided for actuating the arm 30 when the wax is solid.

The switch after being closed is automatically 25 opened on the melting of the wax, due to the heating of the spring 25 through an overload, when the lever 28 is swung downwards due to the pressure of the spring loaded roller 35 acting upon the wheel 34 being greater than the tension of the 30 part of the spring 25 which is immersed in the softened or melted wax substance, the extensions 31 then form contact with the ramp 32, and the tension of the spring 33 causes these extensions 31 to ride up the ramp 32 and swings the arm 30 35 clear of the roller 35, when the circuit is broken the tension of the spring 35 after breaking the circuit returns the lever 28 to its normal position, and as soon as the wax becomes solid the switch can be closed by moving the grooved pulley 34 40 into contact with the roller 35. Any suitable mechanical means may be applied for effecting the closing of the switch when the wax is solid. The switch can be opened when the wax is solid by swinging the arm 30 away from the roller 35 45 when the springs 37 and part of the spring 25 above the wax substance is compressed to allow the pulley 34 to move away from the roller 35.

Referring to Fig. 4 a container is supported by a helical spring 40 which is connected to a roller 50 or ball contact member 40^a on the base of the container 39, the upper end of the spring 40 is connected to a conductor 41 fixed to a part of the casing 42. The spring 40 is partly embedded in wax.

A second ball or roller contact member 43 is connected through a helical relief spring 44 to a second contact member 45 fixed to a part of the casing 42. Slidably mounted in the casing 42 between guides 46 is a large ball or roller 47 60 adapted to move between the ball or roller contacts 40^a and 43. Said large contact roller 47 is connected to a plunger 48 for closing the circuit by hand, against the tension of a spring 49 interposed between a socket 50 integral with a ball or roller 47 and a stop 51 fixed to the casing 42.

To close the switch by hand the plunger 48 is pressed inwardly until the large ball or roller has moved between the ball or roller contacts 40^a and 43; during the inward movement of said plunger 70 48, when the wax is solid, the ball or roller 43 is depressed and immediately rises after the ball or roller 48 has passed thereover. When an overload occurs, the wax will melt thereby releasing the spring 40 which allows the container 39 and 75

ball or roller 48 to move upwards through the tension of the spring 49, being greater than the tension of the spring 40 forcing the large ball or roller 48 outwards and breaking the circuit. The 5 circuit can be closed again as soon as the wax becomes solid.

Referring to Figs. 5 and 6 a stationary container 52 partly filled with wax or fusible metal is provided with a blade or leaf spring 53, set in the 10 solid wax and secured to the base of the container 52 and at the upper end to a bush 54 rotatably mounted in the container 52.

A metallic projection 55 fixed to the bush 54 engages with a spring actuated plunger 56 when 15 the circuit is closed. Said plunger 56 is mounted in a barrel 57 which in turn is pivotally mounted on a spindle 58 extending from the side of the container 52. The barrel 57 is rotated in one direction against tension of a spring 59 when closing 20 the switch.

The switch is closed when the wax is solid by moving the spring actuated contact 56 across the projection 55 until it is interposed between said projection 55 and spring 59. Should there be 25 any overheating which is conducted to the wax or metal alloy causing it to melt or soften, the tension of the spring 59 being greater than the tension of the spring 53 rotates the bush 54 and projection 55 and the barrel 57 turns on the spindle 30 58 when the plunger 56 is swung out of contact from the projection 55, and the bush and projection finally return to their normal position.

Referring to Figs. 7 and 8 a container 60 is 35 rotatably mounted through a spindle 61 supported in a bearing 69. A blade spring 63 is partly embedded in wax and anchored to the base 64 of the container, and a terminal 65 is fixed to the upper end of the spring 63, and attached to the base board 65a.

40 A cam shaped catch 66 integral with the container 60 is adapted to engage with switch knife blades 67 as hereinafter set forth. The blades 67 are pivotally mounted (not shown) and fastened together by a metal block 68 provided with an 45 insulated handle 69 for operating the switch. The blades 67 are spread apart by means of a helical spring 70 interposed between them as shown in Figs. 7 and 8, and a fixed thrust plate 71 is adapted to retain the blades in contact with 50 the cam 66 when the switch is closed.

On closing the switch by the handle 69, when the wax is solid the blades are squeezed together on passing over the projection from the side of the container and the fixed thrust plate 70. To 55 open the switch when the wax is solid in the container, the squeezing again takes place. Now the tendency of operating a spring (not shown) upon the blades in a similar manner to the spring 59 acting on the barrel 57 in Fig. 6 is to force the 60 blades outwards, one of the knife blades is held by the projection from the container, therefore it has a force applied which tends to turn the container and at the same time to twist the spring 63. This happens when the wax softens, the 65 blades are swung away from the cam 66 and the container returns to its previous position due to the natural disposition of the spring 63 before the wax becomes solid.

If desired the cam 66 may be fixed to one of the 70 blades 67 instead of upon the container 60, also the blades 67 may move and the container is fixed or vice versa.

I claim:

75 1. A thermally actuated apparatus comprising a container provided with a wax substance, a

resilient member connected within the said container embedded in the wax and capable of movement in relation to said container when the wax substance is in a softened state, mechanical means associated with at least one of the moving parts being automatically actuated by the relative movement between said container and resilient member on the softening of the wax substance, said resilient member tending to restore the normal relative position of said container and resilient member while the wax is in a softened state, and means for operating the apparatus when the wax substance is in a solid state without altering the relative position of the container and the resilient member. 10 15

2. A thermally actuated apparatus comprising a container provided with a wax substance, a spring embedded in said wax fixed to the base of the container, a movable contact member connected to said spring outside the wax, a locking means engaging said movable contact member when the wax is solid, a contact member being automatically released from the locking means on the softening of the wax and means for operating said locking means when the wax is solid. 20 25

3. A thermally actuated apparatus comprising a container, a wax substance therein, a spring embedded in said wax fixed to the base of the container, a movable contact member connected to said spring, a spring associated with said movable contact member of greater tension than the first mentioned spring, a locking means co-operating with said movable contact member automatically released on the softening of the wax substance, and means for actuating the locking member 30 35 when the wax is in a solid state.

4. A thermally actuated apparatus comprising a container, a wax substance therein, a spring embedded in said wax fixed to the base of the container, a fixed rod, a rocking lever slidably 40 mounted upon said rod, means for limiting the movement of said rocking lever, a locking means co-operating with said rocking lever at one end automatically released therefrom on the softening of the wax substance, the opposite end of said 45 rocking lever fixed to the spring and means for operating said locking means when the wax substance is in solid state.

5. A thermally actuated apparatus comprising a container, a wax substance therein, a spring 50 embedded in said wax fixed to the base of the container, a fixed rod, a rocking lever slidably mounted on said rod, a stop limiting the movement of the rocking lever in one direction, a 55 spring of greater tension than the first mentioned spring limiting the movement of said rocking lever in the opposite direction, a locking means co-operating with said rocking lever automatically released on the softening of the wax substance and means for operating said locking 60 means when the wax substance is in a solid state.

6. A thermally actuated apparatus comprising a container, a wax substance therein, a helical spring with convolutions of two diameters 65 embedded in the wax substance fixed to the base of the container, a fixed rod, a rocking lever slidably mounted upon said rod, means for limiting the movement of said rocking lever, one end of said rocking lever fixed to the spring, a locking 70 means engaging with the other end of the rocking lever, a tripping means releasing said locking means when the wax is solid and said locking means automatically released on the softening of the wax substance. 75

7. A thermally actuated apparatus comprising a container, a wax substance therein, a helical spring with convolutions of two diameters embedded in the wax substance fixed to the base of the container, a fixed rod, a rocking lever slidably mounted thereon, connected to the helical spring, a locking means engaging with said rocking lever, a spring controlled plunger co-operating with said rocking lever releasing the locking means when the wax substance is solid and said locking means automatically released on the softening of the wax.

8. A thermally actuated apparatus comprising a container, a wax substance therein, a helical spring with convolutions of two diameters embedded in the wax substance fixed to the base of the container, a pivoted lever connected to said spring, an arm hingedly mounted in said lever, extensions integral with said arm, a slotted ramp,

a resiliently supported catch of greater resiliency than the tension of said helical spring co-operating with the free end of said arm and spring means for moving said extensions along the ramp and swinging the arm away from the catch on the softening of the wax.

9. A thermally actuated apparatus comprising a rotatably supported container, a wax substance therein, a blade spring fixed at one end to said container embedded in the wax substance, a fixed bracket connected to the opposite end of the spring, a cam integral with the container, a blade switch engaging said cam automatically released on the softening of the wax substance and spring means operatively associated with said blade switch actuating the apparatus when the wax is solid.

ARTHUR GEORGE BULLEN.
